US0D1095483S

(12) **United States Design Patent** (10) Patent No.: **US D1,095,483 S**
(45) Date of Patent: ** Sep. 30, 2025

(54) **CAREGIVER NOTIFICATION DEVICE**
(71) Applicant: **Masimo Corporation**, Irvine, CA (US)
(72) Inventors: **Chad A. DeJong**, Los Angeles, CA (US); **Steven Egge**, Laguna Hills, CA (US)
(73) Assignee: **Masimo Corporation**, Irvine, CA (US)
(**) Term: **15 Years**
(21) Appl. No.: **29/866,707**
(22) Filed: **Sep. 23, 2022**
(51) LOC (15) Cl. **14-03**
(52) U.S. Cl.
USPC **D14/191; D10/104.2**
